Primary Examiner — Bridget L Eland

(74) Attorney, Agent, or Firm — St. Onge Steward Johnston
& Reens LLC(57) **CLAIM**The ornamental design for a needle holder, as shown and
described.

DESCRIPTION

FIG. 1 is a front left side top isometric view of a needle holder
in accordance with the new design;

FIG. 2 is a front elevational view thereof;

FIG. 3 is a rear elevational view thereof;

FIG. 4 is a right side elevational view thereof;

FIG. 5 is left side elevational view thereof;

FIG. 6 is a top plan view thereof; and,

FIG. 7 is a bottom plan view thereof.

The broken lines shown in FIGS. 1-3 are included for the
purpose of illustrating portions of the needle holder that form
no part of the claimed design.**1 Claim, 7 Drawing Sheets***FIG. 2*
